UNITED STATES PATENT OFFICE.

RICHARD SELIGMAN, OF WIMBLEDON, ENGLAND, ASSIGNOR TO THE ALUMINIUM PLANT AND VESSEL COMPANY LIMITED, OF LONDON, ENGLAND.

HEAT-INTERCHANGE APPARATUS.

Application filed July 15, 1924, Serial No. 726,084, and in Great Britain July 18, 1923.

This invention has reference to the interchange of heat by means of machinery or apparatus of the kind in which channels or passages for the liquids are constituted by 5 plates provided with facial grooves or ribs which are adapted to furnish an extended or zig-zag course for the liquids, and particularly where such apparatus is employed in the treatment of liquids which it is desirable should be kept rigidly apart or prevented from intermingling.

The present invention relates to certain improvements whereby the apparatus is rendered more particularly applicable for use 15 in the heating and/or cooling of milk, beer or the like and the aim of the invention is to provide a construction which is adapted to ensure the rigid separation of the liquids and a continuous exchange of heat, while 20 affording a high working efficiency and greater facility for access and cleaning.

According to this invention the aforesaid rigid separation of the liquids is obtained by associating plates of the kind herein referred to and so arranging the joints that any leakage past one is unable to reach another but will fall clear of the machine. The faces of the plates are formed with 25 countersunk grooves adapted to receive packing cord or strip of such proportion that, when adjacent plates are nested and secured together by bolting or the like, the packing cord, under pressure of the tightened plates, will become distorted and, while 30 completely filling the said groove, will allow the adjacent surfaces of the plates to make intimate contact and preserve the separation of the liquids. One of the passages for the liquid to or from the plates may be 35 within this joint arrangement and the other without a separate joint of similar or different shape may be accommodated in a groove around the outer passage. A groove may be provided between the joints to enable liquid 40 that may leak past either of the joints to be collected and to be delivered clear of the machine.

According to a modified method of obtaining the rigid separation of the liquids 45 one of the latter is passed through passages exterior to the main joint just above de-

scribed and the other admitted to grooves within the main joint by way of passages formed in the plates and connected on the exterior with a header for parallel working 55 or by inter-connecting elbows where the liquid is intended to pass from plate to plate in series. Both liquids may however be dealt with according to either of the methods just referred to.

When employing plates having ribs which form grooves or channels the arrangement is preferably such that the latter are in parallel order and in communication, the long continuous zig-zag passages extending to-and-fro from side to side or edge to edge of the plates. The liquids are admitted to and exhausted from the conduits or passages by means of connections or orifices formed or provided in the frame portions of 70 the plates.

Assuming a number of the aforesaid plates to be employed the liquid to be heated may be admitted to and passed through the conduits in alternate plates, the entry being at the top and the exit at the bottom, and the heating liquid admitted to the other plates, the entry being at the bottom and the exit at the top. In such a method, the plates would be working in parallel and the 75 heat exchange effected by counter current.

The liquids may however be caused to pass in series from the one plate to the next but one in opposite directions, i. e., in zig-zag fashion through the passages formed by 85 alternate pairs of plates in which case counter current heat exchange in series would result.

The arrangement may however be such that while one liquid is caused to pass in 90 series the other liquid may be conducted through passages in parallel.

If desired the plates may be arranged for working in pairs or sets, an appropriate heat insulating plate or material being interposed as a separating medium.

In some cases the plates may be of combined or double construction having internally formed channels or passages which may be of a character similar to the grooves 100 or channels in the faces of the plates and run parallel therewith. The use of such a double

plate has the great advantage of reducing the number of joints while an economy in the cost of manufacture is effected.

By making the grooves or channels very small a high rate of speed may be obtained by the liquid and consequently a high rate of heat interchange.

The improved apparatus tends to greater efficiency in working and compactness of

construction. The channels are very readily cleaned as upon taking the plates apart the grooves or channels are exposed and may be cleaned by the application of an ordinary brush.

In order that the invention may be readily understood and carried into effect same will now be more fully described with reference to the accompanying drawings, in which:—

Figure 1 is a view in section shewing a construction of grooved or channelled plate in connection with a header channel.

Figure 2 is a similar view shewing a construction of plate in which grooves or channels are formed on each face a separating plate being interposed which extends beyond the main joint but does not reach the secondary joint, the space thus left providing a passage for the escape of liquid leaking past either joint.

Figure 3 is a view partly in elevation and partly in section shewing a plate provided with grooves or channels on each outer face and an intervening or central through channel.

Figures 4, 5, 6 and 7 are fragmentary sections taken on the lines 4—4, 5—5, 6—6 and 7—7 respectively of Figure 3.

Figure 8 is a detail view of the rubber or yielding joints in the lugs pertaining to the plates showing grooves whereby liquid leaking past either these joints or the main joints may escape.

Figure 9 is an end view, Figure 10 a side view and Figure 11 a plan corresponding with Figure 9 of an arrangement of apparatus according to the invention.

Figures 12, 13 and 14 are views respectively similar to Figures 9, 10 and 11 showing an arrangement wherein two connections are in the head and two in the sides of the plates.

Figure 15 is a side view and Figure 16 a corresponding plan showing an arrangement in which the connections are made directly in the plates.

Figure 17 is a part elevation and section of a combined or double form of plate applicable for use in carrying out the present invention, the upper half of the figure showing, the channels formed on the exterior of the plate and one of the admission or exhaust passages pertaining thereto and the lower half the interiorly formed channels or through ways and one of the admission or exhaust passages pertaining thereto.

Figure 18 is a view similar to Figure 17 showing a plate having interiorly formed channels only the exterior faces of the plate being plane surfaces, the upper half of the figure shows the plane or flat exterior surface of the plate and the lower half the interiorly formed channels and one of the admission or exhaust passages pertaining thereto.

Figures 19, 20 and 21 show plates as illustrated in Figures 17 and 18 arranged together in the manner of assembling the same in installing a complete apparatus.

Figure 19 is a transverse section taken on the line 19—19 in Figure 17.

Figure 20 is a transverse section taken on the line 20—20 in Figure 17.

Figure 21 is a view similar to Figure 19 showing a means of causing liquid to pass from one plate to another in series.

Referring to Figure 1 the plate *a* is formed or provided with grooves or channels *a*¹ constituted by the ribs *a*² which project from one face of the plate the other face of the plate being plain or flat and smooth so that when a number of such plates are placed together inter-enclosed spaces are formed constituting the grooves or channels *a*¹. The ribs *a*² are so arranged as to render the channels in zig-zag fashion so that a long path is provided for the liquid.

The plain face of each plate is countersunk or formed with a groove *a*³ for the reception of a resilient packing cord or strip *a*⁴ which becomes compressed and distorted upon the plates being tightened together.

In this figure the plates *a* are shown in connection with a header channel *b* through passages *c* formed in lateral extensions *c*¹ of the plates, the extensions being connected with the header channel *b* by union joints *d*.

If it be desired to pass the liquid in series from the one plate to the next but one, the header channel *b* would be replaced by appropriate elbows.

In Figure 2 the plates are shown formed with a central web *a*⁵ and grooves or channels *a*¹ *a*¹ on either side thereof. A sheet of metal *a*⁶ is arranged between the plates which separates the grooves *a*¹ and furnishes a space *a*⁶⁰ for escape of liquid. The grooves or channels in this arrangement are in communication with the passage *b*⁵, provided by the lugs *c*⁵ which are extensions of the plates by way of the passages *c*⁶.

In order to render the apparatus liquid-tight a series of joints of substantially known construction are provided between the several lugs *c*⁵. One face of the plate is grooved around the aperture *b*⁵ for the reception of a resilient ring *e*, which is preferably formed with a depressible inwardly projecting lip or flange *e*¹. Upon the plates being tightened together this flange *e*¹ admits of a perfectly close and liquid tight joint being ef-

fected between the parts. The effect of tightening the plates together is illustrated in this Figure 2.

In Figure 8 the lug c^x is shown grooved on each face and provided with the aforesaid resilient packing e the plates being formed with a groove a^7 for the escape of any liquid that may leak past the joints as hereinbefore described.

10 Referring now to Figures 3 to 7 inclusive, the plate is formed on each face with grooves or channels a^1, a^1 and an intervening through channel f . The channels a^1, a^1 are in communication with the liquid supply a^5 and the 15 exit a^6 and the through channel with the supply f^1 and exit f^2 . Thus in this arrangement assuming milk is being heated or cooled by means of hot or cold water, the milk which passes through the narrow channels a^1 enters by the slot a^5 and passes out by way of the slot a^6 while the water enters by the opening f^1 passes along the passages f and escapes by way of the port f^2 . The direction of flow may however be reversed as will be readily apparent.

Figures 5 and 7 show the intervening through-channel f as a separate plate structure.

It will be understood that the plate may 30 be used with the passages vertical or it may be used with the passages horizontal; lugs g, g^1 serve to support and guide the plates upon g^1, g^1 shown in the figures now to be referred to.

35 Figures 9, 10 and 11 illustrate an arrangement of the apparatus adapted for direct heating or cooling wherein the two liquids run in parallel and in opposite directions to one another. In this connection the combined form of plate (see particularly Figures 3 and 6) is suitable, the inlets h, h and outlets i, i^1 being arranged in the cover k of the machine and the inlets and outlets on the plates co-axial with the said cover 40 inlets and outlets. By means of this construction and arrangement all the exterior connections may be left intact while the machine is opened for cleaning or otherwise.

In Figures 12, 13 and 14 the cover k^1 is 50 provided with two inlets (or outlets) h, i and the sides of one of the plates with outlets (or inlets) h^1, i^1 communicating with channels formed by the holes in the plates as shown in Figure 6.

55 A further arrangement is shown in Figures 15 and 16 in which the inlets and outlets are carried independently of the cover k^x . The water connections for example are shown as lateral flanges l, l^1 and (e. g.) the milk connections as screwed joints m, m^1 .

Referring now to Figures 17 to 20 inclusive, from which the arrangement and assembly of the plates in installing a complete apparatus and the manner of passing the liquids into and through the machine will

be readily understood, the combined or double plate is indicated by the reference number 1 and the plates with interiorly formed channels only by the reference number 2.

70 Each plate 1, 2, is formed on opposite sides thereof, with an extension or lug 3, 3¹ having a transverse passage or bore 4, 4¹ respectively. These passages or bores 4, 4¹ are in communication with the exterior channels or passages 5 formed in each face of the plate 1 by way of openings 6, 6¹. Thus milk, for instance, admitted to the passage or bore 4 finds ingress through the opening 6 to the channels or passages 5 and after traversing 80 the said channels finds egress from the latter by way of the corresponding openings 6¹ to the passage 4¹ in the lug or extension 3¹ at the opposite side of the plate.

85 Similarly each plate 1, 2, is formed on opposite sides with an extension or lug 7, 7¹ having transverse bores or throughways 8, 8¹ respectively. These throughways 8, 8¹ are in communication with the interiorly formed channels or passages 9, in each plate 1, 2 90 by way of openings 10, 10¹ respectively, so that water, for example, admitted to the throughway 8 in the lug or extension 7 passes through the opening 10 to the channels or passages 9 and escapes from the latter by way of the corresponding openings 10¹ into the transverse passage 8¹ in the lug or extension 7¹ at the opposite side of the plate.

95 Upon assembling a number of plates 1 and 2 to constitute a complete machine or apparatus according to this invention it will be seen that the throughways 4, 4¹ and 8, 8¹ in the respective lugs 3, 3¹ and 7, 7¹ are open to their respective channels or passages 5 and 9 but are closed as regards intercommunication so that, assuming milk is being treated, that liquid will be confined to the channels or passages 5 while the water will be similarly confined to the passages 9 owing to the throughways 8, 8¹ being open to the 100 channels or passages 9 but closed to the channels 5.

105 The lugs or extensions 3, 3¹ and 7, 7¹ on one plate serve as distance pieces or communicating channels to the similar lugs on adjacent plates.

110 My means of a groove a^7 any liquid that may leak past the joints a^4 and e^1 is allowed to escape.

115 In the foregoing description the liquids or fluids have generally been referred to as passing through the machine comprising a number of plates as herein described in parallel. It will however be readily understood that they may be caused to pass from one plate to another in series by means of a suitable arrangement of ports.

120 In order expeditiously to change the direction of flow of either liquid removable or interchangeable plugs may be adapted 125

for being placed in any of the ports so that the machine may serve for instance for heating by parallel flow and cooling by series flow in quick succession. Such a method 5 of operating is illustrated in Figure 21 from which it will be seen that the bore or passage 4 in the upper side of plate 1 is filled with a solid plug 11 while the bore or passage 4¹ in the lower side of each adjacent 10 plate 2 is similarly filled with a solid plug 12. If now milk, for example, be introduced into the bore 4 at the right-hand side of the figure, the milk passing through and flowing along the said bore 4 will be deflected by the plug 11 into the opening 6, on that side of the plug, emerging therefrom into the channels 5 that occur in the same plane and when the milk has traversed the said channels (5) it passes into the bore 4¹ 20 at the lower end of plate 1 and re-traverses the said plate by way of the opening 6¹ and channels 5 on the left hand side, finding egress at the upper end of the plate 1 by way of the opening 6 into the bore or passage 4 on the left hand side of the plug 11. The plugs 12, 12 confine the milk to the channels and passages in plate 1.

I claim:—

1. Plate apparatus for heat interchange 20 which comprises plates having a ribbed surface whereof the ribs are arranged in parallel order and form, to and fro of the plates, long continuous zig-zag communicating channels, plates having plane surfaces 30 for contacting with the said ribbed plates and side closing the said channels, admission and exhaust passages to and from the said channels, countersunk grooves about the margins of the said ribbed plates and 40 the said admission and exhaust passages, resilient packing cord in the said countersunk grooves and means for exerting pressure on the said plates whereby the said packing cords become compressed and distorted diametrically and the joints between the said plates rendered liquid tight.

2. Plate apparatus for heat interchange 50 which comprises a series of plates each having ribs on each face arranged in parallel order and forming, to-and-fro of the plates, long continuous zig-zag communicating channels, a series of interposed plane face plates for contacting with the faces of the said ribbed plates and side closing the said 55 channels, admission and exhaust passages to and from the said channels, countersunk grooves about the margins of the said ribbed faces and adjacent the said admission and exhaust passages, resilient packing cord located in the said countersunk grooves, and means for exerting pressure on the said plate series whereby the said packing cords are compressed and distorted diametrically and the joints between the said plates rendered liquid tight.

3. Plate apparatus for heat interchange which comprises a series of plates having a ribbed surface whereof the ribs are arranged in parallel order and form, to-and-fro of the plates, long continuous zig-zag 70 communicating channels, a series of plates having plane surfaces for contacting with the said ribbed plates and side closing the said channels, apertured lugs extending from each plate in each series of plates to provide admission and exhaust passages for the liquids to and from the said channels, countersunk grooves about the margins of the said ribbed plates and adjacent the said admission and exhaust apertures, resilient 80 packing cord in the said countersunk grooves and means for exerting pressure on the several plate series whereby the said packing cords are compressed and distorted diametrically and the joints between the said plates 85 rendered liquid tight.

4. Plate apparatus for heat interchange which comprises a series of plates each having ribs on each face arranged in parallel order and forming, to-and-fro of the plates, long continuous zig-zag communicating channels, a series of interposed plane face plates for contacting with the faces of the said ribbed plates and side closing the said channels, apertured lugs extending from each of the said plates to provide admission and exhaust passages for the liquids to and from the said channels, countersunk grooves about the margins of the said ribbed faces and adjacent the said admission and exhaust apertures, resilient packing cord located in the said countersunk grooves, and means for exerting pressure on the said plate series whereby the said packing cords are compressed and distorted diametrically and the joints between the said plates rendered liquid tight.

5. Plate apparatus for heat interchange which comprises a series of plates each having ribs on its face arranged in parallel order and forming to-and-fro of the plates, long continuous zig-zag communicating channels, a series of plates each having plane surfaces for contacting with the said facially ribbed plates and side closing the said channels, apertured lugs extending from each of the plates of each series to provide admission and exhaust passages for the liquids to and from the said channels, countersunk grooves about the margins of the said facially ribbed and channelled plates, resilient packing cord in the said countersunk grooves to constitute the main joints in the plate assembly, countersunk grooves adjacent the aforesaid admission and exhaust apertures, resilient packing cord in the said last mentioned countersunk grooves to constitute secondary joints in the passages for the liquids, the passage for one liquid being within the said main joint

and the passages for the other liquid without the said joint, and means for exerting pressure on the plates whereby the said packing cords become compressed and distorted diametrically and the said joints rendered liquid tight.

6. Plate apparatus for heat interchange which comprises a series of plates each having ribs on each face arranged in parallel order and forming, to-and-fro of the plates, long continuous zig-zag communicating channels, a series of interposed plane face plates for contacting with the faces of the said ribbed plates and side closing the said zig-zag channels, apertured lugs extending from all the said plates to provide admission and exhaust passages for the liquids to and from the said channels, countersunk grooves about the margins of the faces of each ribbed plate, resilient packing cord in the said countersunk grooves to constitute the main joint between the plates of the several series, countersunk grooves adjacent the aforesaid admission and exhaust apertures, resilient packing cord in the said last mentioned countersunk grooves to constitute secondary joints in the said admission and exhaust passages, the passages for one liquid being within the said main joint and the passages for the other liquid without the said joint and means for exerting pressure on the plates whereby the said resilient packing cords become compressed and distorted diametrically and the said joints rendered liquid tight.

7. In plate apparatus for effecting interchange of heat, the combination of a series of facially grooved plates with a series of plates having plane surfaces adapted to contact with said grooved faces and to close the aforesaid grooves, apertured lugs extending from each of said plates to provide admission and exhaust passages thereto and therefrom, countersunk face grooves in the facially grooved plates, resilient packing cords located in said grooves adapted to constitute the main joint between adjacent plates and to embrace one set of said admission and exhaust passages and a secondary joint for the said admission and exhaust passages not embraced by said main joint.

8. In plate apparatus for effecting interchange of heat, the combination of a series of facially grooved plates with a series of plates having plane surfaces adapted to contact with said grooved faces and to close the aforesaid grooves, apertured lugs extending from each of said plates to provide admission and exhaust passages to and from the channels, countersunk face grooves in the facially grooved plates and resilient packing cords located in said grooves adapted to constitute the main joint between adjacent plates and to embrace one of the admission and exhaust passages, a secondary

joint for the said admission and exhaust passages not embraced by said main joint and a groove formed in the faces of the plates outside the main joint and between the latter and the secondary joint to conduct away leakage from either of said joints.

9. In plate apparatus for effecting interchange of heat, the combination of a series of facially grooved plates with a series of plates having plane surfaces adapted to contact with said grooved faces and to close the aforesaid grooves, apertured lugs extending from each of said plates to provide admission and exhaust passages to and from the said channels, connecting passages formed in the frame portions of the facially grooved plates, countersunk face grooves in the facially grooved plates, resilient packing located in said grooves adapted to constitute the main joint between adjacent plates and to embrace one of the admission and exhaust passages and a secondary joint for the admission and exhaust passages not embraced by said main joint.

10. In plate apparatus for effecting interchange of heat, the combination of a series of facially grooved plates, with a series of plates having plane surfaces adapted to contact with said grooved faces and to close the aforesaid grooves, apertured lugs extending from each of said plates to provide admission and exhaust passages to and from the grooves, connecting passages formed in the frame portions of the facially grooved plates, countersunk face grooves in the facially grooved plates, resilient packing located in said grooves adapted to form the main joint between adjacent contacting plates and to embrace one set of admission and exhaust passages, a secondary joint for the admission and exhaust passages not embraced by said main joint and a groove formed in the faces of the plates outside the main joint and between the latter and the secondary joint to conduct away leakage from either of said joints.

11. Plate apparatus for heat interchange which comprises a series of plates each having ribs on each face arranged in parallel order and forming to-and-fro of the plates, long continuous zig-zag communicating channels, a series of plates each having plane surfaces adapted to contact with the said ribbed faces and to side close the said zig-zag channels, apertured lugs extending from all of said plates to provide admission and exhaust passages to and from the channels, countersunk face grooves in the facially ribbed and channelled plates, resilient packing cord located in said grooves adapted to constitute the main joint between adjacent contacting plates and to embrace one set of admission and exhaust passages, countersunk grooves adjacent the admission and exhaust apertures not embraced by said main

joint, resilient packing cord in said last mentioned grooves to constitute the secondary joint, means for exerting pressure on the plates whereby the said packing cords be-
5 come compressed and distorted diametrically and the said joints rendered liquid tight, and a groove formed in the faces of the

plates outside the main joint and between the latter and the secondary joint to conduct away leakage from either of said joints. 10

In witness whereof I have hereunto subscribed my signature.

RICHARD SELIGMAN.
